UNITED STATES PATENT OFFICE.

PAUL SCHUYLER VAN BLOEM, OF HEMPSTEAD, NEW YORK, ASSIGNOR TO THE VIKING PRODUCTS CORPORATION, OF NEW YORK, N. Y., A CORPORATION OF NEW YORK.

WINDOW ILLUMINATOR AND SIGN.

Application filed December 7, 1921. Serial No. 520,610.

To all whom it may concern:

Be it known that I, PAUL SCHUYLER VAN BLOEM, a citizen of the United States, and resident of Hempstead, in the county of Nassau and State of New York, have invented certain new and useful Improvements in Window Illuminators and Signs, of which the following is a specification.

The main object of this invention is to provide a device which will serve both as a window sign and window illuminator. The device consists preferably of a long box or casing adapted to be placed in a show window so that its front wall will face the window and its rear wall will be placed toward the articles on display in the window. The front wall of the device is designed to carry the sign portion and the rear wall of the device is formed of a light-transfusing plate, preferably of glass, through which the light from the device will pass to the goods displayed in the window.

In the drawings, Fig. 1 is a front elevation of the illuminator and sign;

Fig. 2 a rear elevation partly in vertical section;

Fig. 3 a view similar to Fig. 2 showing a series of colored glass screens mounted in the rear wall of the device;

Fig. 4 a transverse vertical sectional view of the device as arranged in a show window, a portion of the show window being also shown in section; and

Fig. 5 a transverse vertical sectional view of a slightly modified form of the device.

Referring to the various parts by numerals, 1 designates the bottom wall of the device and 2 the top wall thereof. These two walls are connected by vertical end walls 3; and all of these walls are preferably of sheet metal or other light and strong opaque material. The front wall of the device is formed by an opaque stencil plate 4, said plate being preferably of thin sheet metal.

This stencil plate is connected to the top and bottom walls and to the end walls in any suitable manner. As shown in Fig. 4, the upper and lower edges thereof are bent inwardly to form flanges which are securely attached to the upper and lower walls by means of suitable devices. The stencil plate is provided with openings which correspond in shape with the shape of the letters and characters to be displayed. In these openings are inserted glass letters 5, said letters

extending through the openings and projecting beyond the outer face of the stencil plate. Each letter is formed with an enlarged base portion 6 which is adapted to fit against the inner face of the stencil plate, said base portion being of glass or other transparent material. Secured to the inner side of the stencil plate below the openings therein is a supporting flange 7, said flange serving as an aligning bar to align all of the displayed letters in the sign, said bar extending longitudinally of the stencil plate and being permanently secured thereto. This aligning bar and support is formed with the upwardly extending retaining flange 8. Back of the letters is supported a light-diffusing plate 9, said plate resting at its lower edge on the aligning bar and being held thereto by the retaining flange 8. Removably secured to the stencil plate above the openings therein is a longitudinally extending retaining clip 10, said clip serving to hold the light-diffusing plate and the letters in position on the stencil plate. This retaining clip is preferably removably attached to the stencil plate by means of nuts and bolts 11. By removing said retaining clip the diffusing plate and the letters may be readily removed and replaced. To the outer surface of the stencil plate, around the marginal edges thereof, is secured a rim or bead 12 in order to provide a pleasing finish to the face of the sign. The diffusing plate 9 may be of ground glass, or it may be a sheet of glass of any desired color if it be desired to give color to the letters displayed in the sign. Any form of plate may be used which will prevent the direct rays from the lights within the casing passing outwardly through the clear glass letters. If desired, the light diffusing means may be formed directly on the backs of the glass letters by grinding or cutting them in any manner to produce the desired effect.

Along the rear edge of the bottom wall of the casing are formed two upwardly extending flanges 13 which are placed apart to form a longitudinally extending channel along the rear edge of said bottom wall. The rear edge of the top wall of the casing is bent inwardly to form a shoulder 14 and then downwardly to form the retaining flange 15. The flange 15 extends longitudinally of the casing. The rear wall of the casing is formed of a sheet of glass 16 whose

lower edge rests in the channel between the flanges 13 and whose upper edge rests on the flange 15. The flanges 13 and 15 are so located that the glass sheet 16 inclines upwardly and forwardly, that is to say, upwardly and toward the front wall of the casing. The front wall of the casing, formed by the stencil sheet, extends upwardly and rearwardly, that is to say, upwardly and 10 toward the rear wall of the casing. The forward part of the bottom wall inclines upwardly and forwardly in order to raise the lower edge of the front wall a considerable distance above the bottom of the casing. 15 The purpose of this is to so elevate the lower edge of the front wall that the entire front wall of the casing will be nicely visible through the show window glass and will not be obstructed by the usual retaining beads 20 and strips that are commonly used in securing the show window glass in position.

The rear wall of the casing may be formed of a sheet of ordinary ground glass, or any desired color screen may be used as a light-diffusing means. It is obvious that if it 25 is desired to throw any particular color on the objects displayed in the show window, it will only be necessary to place the desired color screen in the rear wall of the 30 casing. It is also obvious that the light-diffusing plate 9 may be made in sections and each section may be of any desired color.

Within the casing and on the bottom thereof is a sheet metal channel or conduit 35 17, said conduit forming a longitudinally extending housing to receive electric circuit wires. These wires are passed through a nipple 18 in one end of the casing and are then carried throughout the length of the 40 casing within the conduit 17, protecting the wires and concealing them. On the housing or conduit 17 is mounted a suitable number of standards 19 which carry electric lamp sockets 20 at their upper ends. In 45 these sockets suitable lamps 21 are secured. The device is preferably provided with supporting feet 23.

When it is desired to have access to the 50 interior of the casing, the light diffusing plate 16 may be readily removed by first drawing outwardly the upper edge of the said plate to free it from the shoulder 14. The entire sheet of glass may then be withdrawn from the channel formed by the flanges 13. 55 When the rear wall 16 of the device is removed access may be had to the entire interior of the device for the manipulation of the lamps and the removal and replacement of the sign letters and the plate 9.

60 In Fig. 3 the rear wall of the casing is made up of a series of color screens 16^a, of any desired color.

In Fig. 5 the front wall of the casing is 65 vertical and the rear wall is extended upwardly and rearwardly and angularly dis-

posed with respect to the front wall. In the form of the device shown in Fig. 5, the stencil plate is secured to the inner surfaces of flanges 22, said flanges forming the upper and lower marginal edges of the 70 front wall of the casing and serving to frame the stencil plate and to give a finish to the marginal edges of the said front wall.

From the foregoing it is manifest that 75 I provide a self-contained illuminated sign and show window illuminator. The opaque stencil plate and the opaque top and bottom walls of the casing prevent the passing of light rays from the casing except through the glass letters in the front of the 80 casing and through the light diffusing plate in the rear wall of the casing. This gives a very brilliant illumination of the sign letters and also provides means by which the rays of light from the sign illuminating 85 lamps may pass rearwardly into the show window for illuminating purposes. The device may be readily and bodily removed from the show window, and may be moved or shifted about into any desired position. 90

If it be desired to get the full illuminating effect of the lamps on the goods displayed in the show window, the light diffusing plate 16 may be removed leaving 95 the rear side of the device open. It is preferred, however, to use the light diffusing plate 16 in order to soften the light and soften the shadows on the window display.

What I claim is:

1. A window illuminator and sign comprising a closed elongated box or casing formed with opaque bottom and top walls, ends connecting the top and bottom walls, a front wall, a transparent sign carried by said front wall, a light diffusing plate forming the rear wall of the casing, the said plate inclining upwardly and toward the front wall of the casing to increase the vertical area of illumination, means for removably mounting the light diffusing plate upon the casing comprising a support at the rear edge of the bottom wall adapted to loosely hold the lower edge of the plate in place and a rest at the rear edge of the upper wall to support the plate at its upper edge, and a lamp within the casing. 110

2. A window illuminator and sign comprising an elongated box formed with opaque bottom and top walls and with opaque ends connecting the bottom and top walls, a front wall, a transparent sign carried by said front wall, a pair of upwardly extending flanges along the rear edge of the bottom of the casing to form a channel, a downwardly extending flange formed along the rear edge of the top wall of the casing, a removable light diffusing plate, the lower edge of said plate fitting in said channel and the upper edge thereof bearing against 120 said downwardly extending flange. 125

3. A window illuminator and sign comprising a closed elongated box or casing formed with opaque bottom and top walls and with opaque ends connecting the top and bottom walls, a front wall, a transparent sign carried by said wall, a pair of flanges along the rear edge of the bottom of the casing, a downwardly extending flange formed along the rear edge of the top wall of the casing, a removable light-
diffusing plate froming the rear wall of said casing, the lower edge of said plate fitting in said channel and the upper edge thereof bearing against said flange, the front and rear walls of the casing inclining upwardly and toward each other, and a lamp within the casing.

In testimony whereof I hereunto affix my signature.

PAUL SCHUYLER VAN BLOEM.
